UNITED STATES PATENT OFFICE.

ABRAHAM BRAHADI, OF MONTREAL, QUEBEC, CANADA.

HAT.

SPECIFICATION forming part of Letters Patent No. 372,514, dated November 1, 1887.

Application filed August 10, 1887. Serial No. 246,640. (No model.) Patented in Canada April 16, 1887, No. 26,456.

To all whom it may concern:

Be it known that I, ABRAHAM BRAHADI, of the city of Montreal, in the district of Montreal and Province of Quebec, Canada, have invented certain new and useful Improvements in Hats, (for which I have obtained from the Dominion of Canada Letters Patent No. 26,456, under date of April 16, 1887;) and I do hereby declare that the following is a full, clear, and exact description of the same.

My invention has reference to that class of hats known as "pull-overs," and its special object is to enable these to fit better and accommodate themselves more easily to the head of the wearer.

The pull-overs at present in use are made by stretching over a body or shape, usually of cotton, and blocked into the desired form and then covered over the entire surface of the crown and upper side of the brim with adhesive liquid, a cap of soft felt, called the "pull-over covering," which adheres to the whole surface of the shape, so as to produce when dry a hat with stiff brim and crown. Although these hats are very durable and any injury to them can be easily repaired, they present this disadvantage that the shape rarely fits the head of the wearer properly, the stiff edge pressing unevenly upon parts and not accommodating itself to the contour of the head. To remedy this defect and to produce a hat which shall combine with the stiff crown of the ordinary pull-over the adaptability to the head of the ordinary soft felt hat is the object of my invention.

I propose to substitute for the cotton herefore forming the body or shape of the hat soft felt blocked to the form desired, and I further propose to coat the crown of such shape with the adhesive liquid only down to within an inch or two of the bottom, and on the brim

only along its outer edge, so that there will be no stiffness in the bottom part and lower edge of the crown, nor in the brim except along its edge. These parts—viz., the lower part of the crown and the brim—do not differ in any way from the corresponding parts of a soft felt hat, except that the pull-over herein described has two thicknesses of felt instead of one, and that the stiffening of the edge of the brim allows the hat to be taken off in the ordinary way for a salute.

For full comprehension of the invention, reference must be had to the annexed drawing, forming a part of this specification, and being a vertical section of the lower part of the crown and the brim of a pull-over hat embodying my invention, the thickness of the materials being exaggerated to demonstrate more clearly the nature of the invention.

A is the body or shape, made of soft felt or like material, B being the crown portion, and C the rim. This crown portion B is coated with any adhesive compound (shown by E) as far down as the dotted line B' and the brim C only along the edge, as shown at E'. D is the pull-over covering.

What I claim is as follows:

A hat consisting of a complete interior body or structure of soft flexible material blocked into shape and a correspondingly-shaped pull-over or outside structure secured together and stiffened by an adhesive composition, the hat at and for a limited distance above and below the base of its crown being entirely devoid of such stiffening composition, substantially as and for the purpose set forth.

A. BRAHADI.
